UNITED STATES PATENT OFFICE.

ARTHUR H. BOETTCHER, OF CHICAGO, ILLINOIS, ASSIGNOR TO GULBRANSEN-DICKINSON COMPANY, OF CHICAGO, ILLINOIS, A CORPORATION OF ILLINOIS.

MUSICAL INSTRUMENT.

1,402,474.

Specification of Letters Patent.

Patented Jan. 3, 1922.

Application filed October 11, 1915, Serial No. 55,169. Renewed May 14, 1921. Serial No. 469,496.

To all whom it may concern:

Be it known that I, ARTHUR H. BOETTCHER, a citizen of the United States, residing at Chicago, in the county of Cook and State 5 of Illinois, have invented a certain new and useful Improvement in Musical Instruments, of which the following is a full, clear, concise, and exact description, reference being had to the accompanying drawings, forming 10 a part of this specification.

My invention relates to musical instruments and is particularly concerned with piano players or player pianos. As will appear, my invention is applicable to piano 15 players or player pianos, which are operated either pneumatically or electrically. In order to present a full and complete description of my invention, however, by means of an exemplary construction, I shall 20 explain the structure and the mode of operation thereof by reference to a pneumatically operated device.

My invention is concerned particularly with the provision of means for maintaining the proper alignment between the usual perforated note sheet and the usual tracker-board, both well known in the art. As is commonly understood, it is the practice to pass the note sheet from a spool, over the 30 tracker-board, to a so-called "take-up roll," the spool and the roll and the tracker-board being arranged parallel to each other. It is of course necessary to maintain the proper alignment between the openings in the note- 35 sheet and the openings in the tracker-board during the playing operation so that the opening and shutting of the tracker-board passageways may properly take place. I am aware that devices have heretofore been employed for the broad purpose outlined, but in certain respects I am following the teachings of the earlier art in so far as the fundamental principles are concerned. For instance, it is old to maintain the proper 40 feeding of a strip of paper from a roll by providing means for moving the roll slightly from one side to the other, this means being controlled by what may be termed a "test device" engaged by the edge of the strip of 45 paper as it is fed from the roll.

My invention employs precisely this fundamental principle with the exception that it guides the paper to the roll instead of from the roll, the important feature of the

invention residing in the means whereby the 55 roll is moved from side to side.

In following up the point last mentioned, it may be pointed out that it is the theory of the present invention to utilize the turning movement of the roll, which of course is 60 imparted to it in the playing operation, in securing the movement of the roll longitudinal of its own axis and the appended claims are drawn more or less broadly towards a 65 structure having this mode of operation.

In the accompanying drawings, Fig. 1 is a front elevational view of a player piano involving the features of my invention, the front panels having been removed to reveal the interior construction.

Fig. 2 is a view of the roller box and the associated parts, drawn on a larger scale.

Fig. 3 is a detail view of a valve mechanism employed,

Fig. 4 is a sectional view taken on the 75 plane of the line 4, 4 of Fig. 2 looking in the direction indicated by the arrows, and

Fig. 5 is a sectional view taken on the plane of the line 5, 5 of Fig. 2 looking in the direction of the arrows.

Referring first to Figure 1, the piano casting is illustrated at 6, the key-board for manual playing being illustrated at 7. The action is shown at 8, this action having the usual vacuum chamber 9, which by means 85 of a conduit 10 is connected with a wind-chest 11, from which air is exhausted by means of pumper bellows 12, 12, operated by means of the pedals 13, 13.

Upon a shelf 14, suitably set in the case 90 6, a roller-box 15 is mounted, a motor 16 being suitably associated with the roller-box in order to impart rotary movement to the shafts carried in the box, as will be explained.

I shall refer to the details of the roller-box construction by reference to Figure 2, rather than Figure 1, since the illustration is on a larger scale and is more in detail. A tracker-board 17 is mounted in the roller-box and above the tracker-board the stub-shafts 18 and 19 are provided for the reception of a music spool 20, these stub-shafts being suitably journaled in the sides of the box 15. Below the tracker-board 17 100 105 100 a take-up roll shaft 21 is suitably journaled in the sides of the box, this shaft, outside the box, being provided with a gear-wheel

22 which meshes with a pinion 22' adapted to be operatively connected with the motor shaft 23 by means of a clutch 24. The clutch 24 also is adapted to operatively connect the sprocket wheel 25 with the shaft 23, the sprocket wheel 25 being connected by means of the sprocket chain 26 with a sprocket wheel 27 on the shaft 19.

10 A lever 28 is pivoted to the side of the box 15 at 29, the upper end of this lever being adapted to form a drag on the shaft 19 and the lower end being adapted to form a drag on the gear-wheel 22 by means of the brake 30. These features are well-known 15 in the art and need no further description. The arrangement is such that when the pinion 22' is in operative relation to the motor shaft a drag is formed on the shaft 19 and when the position is reversed so that 20 the sprocket wheel 25 is operatively connected with the motor shaft, the drag is placed on the shaft 21, so as to keep the sheet of paper taut in both instances. As shown, and as well known, the paper passes 25 from the music spool 20 to the take up roll 31, mounted upon the shaft 21, during the playing operation and moves in the reverse direction during the re-winding operation.

30 The take-up roll 31 is mounted upon the shaft 21 with a friction grip and a key 32 co-operating with a corresponding key-way in the roll unites the roll with the shaft for angular movement, but permits relative longitudinal movement. At each end thereof 35 of the roll 31 is provided with an axial boss 33, the boss at the left-hand end having a right-hand thread and the boss at the right-hand end having a left-hand thread. With each of the bosses 33, 33 a rising and falling block 34 is arranged to co-operate, the upper face of this block having a thread cut therein, as shown, to correspond to the thread on the boss with which it co-operates. The block 34 is supported and carried upon 40 a vertical rod 35 which is mounted for reciprocation in a tubular support 36 secured upon the base-board 37 of the roller-box, the rod 35 passing through the base-board, as shown. A pin 38 on the rod 35 operates in 45 a slot 39 in the tube 36 so as to prevent angular movement of the rod 35.

50 Below the base-board 37 the rod 35 is connected with the movable board 40 of an actuating pneumatic 41, secured to the underside of a block 42 which, in turn, is secured to the underside of the base-board 37. Normally the interior of the actuating pneumatic 41 is connected with the atmosphere by means of the channel 43, the valve 60 chamber 44 and the port 45 in the base-board 37. The valve 48 is mounted in the valve chamber 44 upon a valve stem 49, this valve being normally seated upon a ring seat 50 and closing the communication between the valve chamber 44 and a tube 51,

which, as shown in Figure 1, leads to the vacuum chamber 9. The lower end of the valve stem 49 is engaged by a diaphragm 52 which covers a diaphragm chamber 53, from which air is normally exhausted by 70 means of the bleeder 54.

75 The primary and actuating pneumatic mechanism which has been described is the same on both sides, the same mechanism being provided for each block 34.

80 A lever 55 is mounted upon a pivot 56 on the side of the roller-box 15. The lower end of the lever 55 is connected by means of a rod 57 with the lever 28, all for a purpose which will be described presently.

85 Mounted in a bushing 58 set in the side wall of the box 15, is an easily sliding rod 59 at the end of which a testing plate 60 is secured. The other end of the rod 59 is provided with a head 61 which is adapted to be engaged by the end of a screw 62 set in a lever 63, the upper arm of which is in the form of a valve 64, adapted to control the openings 65 and 66 in a block 67. The lever 63 is provided with an extension 68 to which 90 a weight 69 is attached, preferably adjustably, in order that the lever may tend to move in a counterclockwise direction, the screw 62 then consequently engaging the head 61 of the rod 59. As illustrated in 95 Figure 2, the test plate 60 is adapted to engage, with suitably light pressure, the edge of the note-sheet *x* and the adjustment is such that when the note-sheet is in proper alignment with the tracker-board 17 the valve 64 100 will just close both of the openings 65 and 66. It will further be apparent that a slight movement in either direction will open one or the other of the openings 65 and 66. The opening 65 is connected by means of a tube 105 70 with the diaphragm chamber 53 of the left-hand rising and falling block 34 and the opening 66 is connected with the corresponding diaphragm chamber of the other block 34 by means of the tube 71.

110 The operation of the device of my invention will now be apparent. Normally the diaphragm chamber 53 is kept exhausted of the air by way of the bleeder 54, the tube 51 and the vacuum chamber 9. This keeps the valve 48 on its lower seat, closing the passageway formed by the ring seat 50 and leaving the passageway or port 45 open. This keeps the actuating pneumatic 41 distended and maintains the engaging block 34 115 in its lower position. This condition prevails in both pneumatic units when both the openings 65 and 66 are closed, as they are when the note-sheet *x* is in proper alignment with the tracker-board. Let us assume 120 now that the note-sheet departs slightly from this proper alignment by shifting slightly to the right. The test plate 60 will, of course, follow it and it follows that the opening 66 will be exposed to the atmos- 125 65 tween the valve chamber 44 and a tube 51.

phere. This means that the diaphragm chamber 53 of the right-hand pneumatic unit will be flooded with air, thus raising the diaphragm, closing off the right-hand actuating pneumatic 41 to the atmosphere and connecting it with the vacuum chamber. Consequently the rod 35 will rise and the right-hand engaging block 34 will engage the corresponding boss 33. This engagement, since under these playing conditions the shaft 21 is being rotated by way of the motor shaft 23, will cause the take-up roll to thread itself towards the left until such time as the opening 66 is closed by the valve 64, this movement being transmitted to the valve by the movement of the test plate 60, which, in turn, is moved by the edge of the note-sheet, drawn back into proper position by the longitudinal movement of the take-up roll. Just as soon as the opening 66 has been closed the valve 48 will drop, the actuating pneumatic 41 will become disengaged and the block 34 will drop to stop the longitudinal movement of the roll.

As before stated, the adjustment at the screw 62 is such that both openings 65 and 66 are closed when the test plate 60 engages the music-sheet in proper alignment with the tracker-board. If the music-sheet should shift in the opposite direction, the opening 65 will be opened to allow the atmosphere to flood the diaphragm chamber 53 of the left-hand pneumatic unit. This will raise the corresponding valve 48 to close off the atmosphere and connect the corresponding actuating pneumatic 41 with the suction. This will raise the left-hand engaging block 34 causing it to rise into threaded engagement with the right-hand screw thread on the left-hand boss 33, the take-up roll then threading itself toward the right until the opening 65 has again been closed. In this way the note-sheet is kept constantly in proper alignment so that the openings therein may register properly with the openings in the tracker-board.

The upper arm of the lever 55 is adapted to engage the head 61 on the rod 59 when the connecting rod 57 is moved to the right by means of the finger-piece 72, this finger-piece being moved over when it is desired to re-wind the note-sheet. As shown, the clutch 24 is moved from one side to the other by means of the movement of the lever 28 through the intervention of a pin 73 and thus when the finger-piece 72 is moved over for re-winding, the lever 55 is moved in a counterclockwise direction so as to draw the test plate 60 away from the note-sheet and keep it in that position while a new music-sheet is being inserted. The valve 64 is so formed as to keep both openings 65 and 66 closed during re-winding and replacing the music-sheet. When the finger-piece 72 is in its left-hand position the upper end

of the lever 55 is entirely disengaged from the rod 59 and it is free to play the proper amount in either direction in order to secure the automatic aligning action which has been described.

It will be clear to those skilled in the art that the pneumatic operation is utilized for the raising of the blocks 34 since the power of the instrument is pneumatic. The same operation may be secured by means of an electro-magnet substituted for the pneumatic unit, the valve 64 instead of controlling a pneumatic circuit, operating as a switch to control electric circuits. I presume that because of the well-known equivalency of these two circuits, it will be unnecessary for me to describe the electric circuit and operating mechanism in detail. The appended claims have been drawn accordingly.

If desired the rotary movement of the shaft 21 may be transformed into longitudinal movement of the tracker-board and it will be equally clear that certain of the appended claims cover a longitudinally movable roll in the combination, whether that roll be the spool or the take-up roll.

I claim:

1. In a player piano, a shaft, a roll having a thread thereon keyed on said shaft, a member movable in a stationary guide for engaging said thread, and means for controlling the movement of said member.

2. In a player piano, a shaft, a music roll keyed on said shaft and upon which a traveling web may be wound and unwound, a member relative to which said web is required to align, means for imparting rotary movement to said roll, a thread on said roll, and a member movable relative to a stationary guide into and out of engagement with said thread.

3. In a player piano, a shaft, a music roll keyed on said shaft and upon which a traveling web may be wound and unwound, a member relative to which said web is required to align, means for imparting rotary movement to said roll, a thread on said roll, and a member movable relative to a stationary guide into and out of engagement with said thread so that when said member engages said thread said roll will move longitudinally.

4. In a strip-registering mechanism, a strip-carrying spool, a revoluble spindle engaged by said spool and capable of endwise movement, said spindle having a screw-threaded part thereon; a movable thread-engaging member normally out of engagement with said screw-threaded part, and mechanism operable by pressure from the moving strip on said strip-carrying spool on edge-wise movement of the strip to move said thread-engaging member into engagement with said screw-threaded part.

5. In a strip-registering mechanism, a strip-carrying spool, a revoluble spindle engaged by said spool and capable of endwise movement, said spindle being provided with 5 parts having screw-threads of opposite lead, a movable thread-engaging member for each of said screw-threaded parts and normally out of engagement therewith, and mechanism operable by pressure from the moving 10 strip on said strip-carrying spool on edge-wise movement of the strip to move the appropriate thread-engaging member into active position.

6. In combination, note sheet mechanism 15 comprising a roller on which a note sheet may be wound or unwound, a tracker bar relative to which said note sheet is required to align, an edge guide responsive to the lateral deviation of said note-sheet, a pair 20 of cooperating threaded members adapted by their relative translational movement to effect a relative shifting adjustment between said note sheet and said tracker bar, an operating member having mechanical connection 25 with said edge guide, and means operated by said operating member for controlling the operation of said threaded members.

7. In combination, note sheet mechanism comprising a roll upon which a note sheet 30 may be wound or unwound, a tracker bar

relative to which said note sheet is required to align, an edge guide responsive to the lateral deviation of said note sheet, a plurality of cooperating threaded members adapted by their relative translational movement to effect a relative shifting adjustment between said note sheet and said tracker bar, a shiftable rod member extending from said edge guide, and means operated by said rod member for controlling the operation of 35 said threaded members.

8. In a device of the class described, in combination with a roller upon which a note sheet may be wound or unwound, of a tracker bar relative to which said note sheet 45 is required to align, an edge guide responsive to the lateral deviation of said note sheet a pair of cooperating threaded members, one of said threaded members being adapted to be rotated, said threaded members being 50 arranged whereby their relative translational motion operates to effect a relative shifting adjustment between said note sheet and said tracker bar, and means connecting said edge guide with said cooperating 55 threaded members for controlling the latter.

In witness whereof, I hereunto subscribe my name this 7th day of October, A. D. 1915.

ARTHUR H. BOETTCHER.

Certificate of Correction.

It is hereby certified that in Letters Patent No. 1,402,474, granted January 3, 1922, upon the application of Arthur H. Boettcher, of Chicago, Illinois, for an improvement in "Musical Instruments," an error appears in the printed specification requiring correction as follows: Page 3, line 94, claim 1, before the word "roll" insert the word *music*; and that the said Letters Patent should be read with this correction therein that the same may conform to the record of the case in the Patent Office.

Signed and sealed this 14th day of February, A. D., 1922.

[SEAL.]

KARL FENNING,

Acting Commissioner of Patents.
